UNITED STATES PATENT OFFICE.

SAMUEL DORFELD, OF BROOKLYN, NEW YORK.

DESIGN FOR A SCALLOPED AND FRINGED LACE BAND FOR CURTAINS.

46,591.

Specification for Design.

Patented Oct. 27, 1914.

Application filed July 6, 1914. Serial No. 849,291. Term of patent 7 years.

To all whom it may concern:

Be it known that I, SAMUEL DORFELD, a citizen of the United States, residing at Brooklyn, in the county of Kings and State of New York, have invented a new, original, and ornamental Design for Scalloped and Fringed Lace Bands for Curtains, of which the following is a specification, reference being had to the accompanying drawing, forming part thereof.

The figure is a plan view of scalloped

and fringed lace bands for curtains, showing my new design.

I claim:

The ornamental design for a scalloped and fringed lace band for curtains, as shown.

SAMUEL DORFELD.

Witnesses:

SAMUEL WILKENFELD,
CHARLOTTE E. KIRSHER.
